UNITED STATES PATENT OFFICE.

WALTER JOSEPH BEASLEY, OF KEW, VICTORIA, AUSTRALIA.

COLLAPSIBLE CASING.

Application filed November 5, 1926, Serial No. 146,403, and in Australia May 14, 1926.

An object of this invention is to provide improved casings of flexible material, as canvas, reinforced with stiffer stronger material, and adapted for the transport of 5 boxed or other goods; and when empty adapted to be folded or rolled into comparatively small space to facilitate return at minimum cost. Each casing will stand easily empty ready to be packed; it is of 10 any suitable size and shape for example rectangular in horizontal section parts being strengthened to resist distortion and withstand wear. For brevity I term the casings bags, but they are adapted to carry articles 15 which would become crushed if packed in ordinary bags or sacks.

Another object is to provide casings which have bodies and lids which have flanges so fastened together as to make it impossible 20 in the event of interference with the contents of the casing to hide external evidence of the fact that interference has occurred. Other objects and advantages of the invention are hereinafter indicated.

25 In the accompanying drawings, in which the scales differ, I illustrate the invention, but various minor details may be modified according to the purposes to which the bags are to be applied.

30 Figure 1 is a perspective view of an erected closed empty bag, parts of which are broken away to show details.

Figure 2 is a sectional view of an upper part of the bag.

35 Figure 3 is a perspective view of part of a bag reinforcing frame.

Figure 4 is a view in vertical section at a lower corner of a bag.

40 Figure 5 is a diagram of a bag having its lid, which is deep in this instance, located clear of its body, except at the hinge, each part being in one of the positions available for packing or unpacking.

The bag has a lid 1, of flexible material, 45 hinged to its body 2, of flexible material, as by sewing along the back as in part seen at 2^a in Figure 1. The lid has a flange 1^b to extend around the body, overlapping and enclosing the top edges 2^b of the body at its sides and front for any desirable depth, the lid top not necessarily fitting close upon the said top edges. With a bag as in Figure 5 the lid top 1^a when in closed position becomes located well above edges 2^b—the lid 55 and body in the case illustrated being of about equal depth, the lid hings 2^a being

about halfway between the bag top and bottom. This allows of the lid and the body being packed separately before they are assembled to form a closed bag. They can 60 be set in other positions than as shown for packing and unpacking purposes.

The lid flange lower edge is reinforced and made stiffer by enclosing in the flexible material a strong wire 6 whereby the flange 65 retains approximately vertical planes. There are in the lid flange holes 5 through which the rings 3 next mentioned project.

The body carries fastening rings 3 of any suitable form, spaced apart, near its top 70 edge, and secured so that at will they can be swung flat against the body. These rings are shown secured by binding 3^a, but could be secured by metal holders. Extending around the top of the body is, except at the 75 back, a flange 4 forming a channel 4^a which is open along its top and entered by the lid flange, flange 4 then covering the lid flange, or its lower part as the case may be.

This body flange has holes 7, usually eyelets or button holes, for the projection outwardly therethrough of parts of the rings 3.

The top edge of flange 4 is reinforced and made stiffer by a bead 8 of strong and less flexible material, shown as a wire whereby the top of the bag will readily keep fully open.

When a bag has been packed and closed an external locking wire 9 is threaded through the rings 3, and drawn tight, its ends then 90 being fixed, a lead seal 10 being illustrated as an example of a fixing means which will enable interferences to be detected. Immediately under the lid top is placed, when predetermined, a reinforcing plate 12 of protective material, for example, stout leather; the preferred area of the plate is that of the underside of the lid.

The bottom of the body is, when predetermined, reinforced by a plate 12^a of preferably the area of the interior surface of the bottom. The bottom illustrated is of two layers of canvas 13, with a plate 13^a intermediate. The empty or partly empty body is made to stand upright by inserting stiffeners of skeleton type, formed of light strips 11 which extend vertically, and 11^a which extend transversely, these strips, which are made of wood for example, being hinged together at 11^b. As shown in Figures 1 and 3, the stiffeners reinforce the bag 105 corners and sides.

The hinges permit of folding the stiffeners when the latter are removed but when in use the upper transverse boards 11^a are set in channels formed by retaining strips 11^a attached to opposite parts of the body, the channels being open along their lower edges. The outer surface of the bag is made wear resisting, by patches 14 of leather carrying studs 15 of metal for example.

10 In some cases the bag has means to allow of inspection of its contents; 16 represents a window, which has a flange to constitute a label retainer.

15 Compartmented partitioning is insertable to increase stiffening and also to locate packed goods but, being well known as applied to wood boxes it is not illustrated.

20 To unpack a bag, I remove its locking wire, and lift its lid. To collapse the bag I remove its reinforcement frames and fold them, and fold or roll the bag. A considerable number of collapsed bags can be conveniently packed for transport purposes in an erected bag; collapsed bags can be carried at 25 will as animal packs.

I claim:—

1. A bag having a body of flexible material and a lid of the same material hinged to the body and having a depending flange to 30 embrace the open end of the body, a flange

for the open end of the body forming a pocket to receive the lid flange, reinforcing means for the open end of the body and edge of the lid flange, and means for fastening the body lid and body flange together in 35 closed position.

2. A bag, as claimed in claim 1, in which the fastening means comprises a series of spaced staples carried by the body adjacent the open end thereof, the lid flange and body 40 flange being provided with opening to admit therethrough the staples when the lid is closed, and locking means to be threaded through said staples.

3. A bag, as claimed in claim 1, including 45 upright and transverse reinforcing members for the corners and sides of the body and hinged connections for the corners to enable the members to fold flat when not in use.

4. A bag, as claimed in claim 1, including 50 upright and transverse reinforcing members for the sides and meeting at their ends to form corners, hinges for the said corners so as to allow folding of the members, and means disposed in the upper portion of said 55 body to receive and embrace the uppermost transverse reinforcing members.

In witness whereof I have hereunto set my hand.

WALTER JOSEPH BEASLEY.
